UNITED STATES PATENT OFFICE.

CHARLES NELSON, OF BROOKLYN, NEW YORK, ASSIGNOR TO S. STERNAU & COMPANY,
OF NEW YORK, N. Y., A COPARTNERSHIP.

DESIGN FOR A CHAFING-DISH AND STAND.

41,325.

Specification for Design.

Patented Apr. 25, 1911.

Application filed February 8, 1908. Serial No. 414,986. Term of patent 7 years.

To all whom it may concern:

Be it known that I, CHARLES NELSON, a subject of the King of Sweden, and residing in the borough of Brooklyn, county of Kings, and State of New York, have invented a new, original, and ornamental Design for a Chafing-Dish and Stand, of which the following is a specification, reference being had to the accompanying drawing, forming part thereof.

The figure is a perspective view of a chafing dish and stand, showing my new design.

The design comprises a chafing dish and stand, the latter having a rectangular top plate provided with a circular opening and mounted on tapering legs of rectangular cross section, said legs terminating in lozenge shaped feet which rest upon a rectangular base. A rectangular lamp support

having a circular opening is carried on the legs by means of straight and curved rectangular arms. A hot water pan of cylindrical shape, having a beaded edge and provided with curved handles carried on angular arms rests within the opening in the top plate. A cylindrical food pan, with a beaded rim and a curved tapered handle of square cross section projecting from one side thereof, rests within the hot water pan. A dome shaped cover, surmounted by a lozenge shaped handle, rests within the rim of the food pan.

I claim:

The ornamental design for a chafing dish and stand, as shown and described.

CHARLES NELSON.
